UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF MAINE.

CORE CAP.

Application filed February 18, 1925. Serial No. 10,052.

This invention has relation to tubular cores or mandrels such as are utilized in winding or reeling paper as delivered from a paper-making machine, but more particularly relates to the metallic caps which are employed in connection with such cores or mandrels when the latter are made of fibrous material. Such cores or mandrels are made of a suitable fabric or paper wound into a tube with the convolutions cemented together by some suitable adhesive material or they are frequently made by winding a web of wet cellulose pulp in such manner that when the same are dried the wall of the tube is substantially homogeneous and non-laminated.

The particular object of the present invention is to provide a metallic cap for use in connection with such cores for protecting the ends thereof and for providing a metallic notch or recess with which the driving members or keys of the winding or reeling mechanism may be engaged.

The invention consists of a drawn sheet-metal cap comprising an inner sleeve and an outer sleeve with an integral rim or web connecting the outer ends of the sleeves, the end of the cap thus formed being notched, and there being a reinforcing member introduced into the annular space between the sleeves and having a notch or recess registering with the notch or recess of the sheet metal cap.

On the accompanying drawings,—

Figure 1 illustrates a core cap embodying the invention.

Figure 2 represents a longitudinal section through the same on the line 2—2 of Figure 1.

Figure 3 represents a reinforcing member.

Figure 4 represents an enlarged section on the line 4—4 of Figure 1 of a part of the core cap.

In accordance with the present invention, the sheet metal portion of the cap is formed of a single piece of sheet metal, which by means of suitable dies and presses is drawn into the form shown in Figure 1 so as to afford an inner sleeve 10, an outer sleeve 11 and a web or rim 12 integral with and connecting the two sleeves. These elements 10, 11 and 12 may be all of the same thickness. Preferably, although not necessarily, the inner sleeve 10 is longer than the outer

sleeve 11. The two sleeves are separated sufficiently to form an annular recess of adequate size to receive therein the end of a core or mandrel 13. I have not deemed it necessary to show a complete core or mandrel, but it will be understood that it is provided at each end with a core cap embodying the present invention. As initially produced, the sleeve 11 preferably flares outwardly as at 14 and the end of the sleeve 10 tapers inwardly at 15 to facilitate the introduction of the end of the core or mandrel into the annular space afforded by the two sleeves. After the cap has been formed as herein described, there is inserted into the annular recess a reinforcing member. This preferably takes the form of a solid metal ring or annulus 16. This is preferably formed of a bar of iron or steel which is bent into cylindrical form with its ends either touching or closely adjacent and of such diameter and dimensions that it may be introduced into the annular recess of the cap and fit friction-tight therein. After the reinforcing member 16 has been inserted in place, a notch is formed by a suitable press through the inner and outer sleeves 11 and 10, the rim or web 12 and the reinforcing member 16 as indicated at 17. By the employment of a suitably formed punch and punch plate for use in such die in forming the notch, the metal of the sleeves and the reinforce is more or less dragged or pinched together as illustrated more or less conventionally in Figure 4. That is to say, the wall of the sleeve 11 is forced inwardly as at 18 and compacted against the metal of the reinforce 16. The latter appears to flow more or less and to be forced inwardly as at 19 against the inner sleeve 10. Thus the sleeves and the reinforce, although not actually welded together, are so interlocked that the ring or reinforce 16 is thereafter incapable of relative movement, and it is unnecessary to spot-weld or otherwise to secure the reinforcing member in position.

Preferably the depth of the notch is not as great as the width of the annular member 16, as indicated by dotted lines in Figure 3, so that below the notch there is a bridge indicated at 20 which forms the inner wall of the notch.

A core cap as herein described consists essentially of a light, sheet metal portion

which constitutes the inner and the outer sleeves and the integral connecting web or rim and a relatively heavy reinforcing member which occupies a portion of the annular recess between the sleeves and which abuts against the rim or web. When the cap is placed upon the end of a tubular core or mandrel, the latter abuts against the reinforcing member.

- 10 Any suitable means may be utilized for interlocking the cap and the end of the core. Preferably the flaring portion 14 of the outer sleeve is pressed or spun into engagement with the exterior wall of the core and the extremity of the inner sleeve 10 is spun or pressed outwardly into engagement with the inner wall of the core or mandrel as shown in Figure 2. Other engaging means may be utilized for connecting the core and the cap together. For example, the two sleeves may be provided with indentations 21, 21, to constitute a key for engaging a slot 22 formed in the end of the core or mandrel.
- 25 A core cap, formed as herein described, is capable of great abuse and rough handling without being distorted or injured. Ordinarily one of the weak points in a core or mandrel is at the notch which is formed 30 therein so as to be engaged by a key or driving member. In the instant case, the walls of the notch are formed in part by the reinforcing member which is capable of 35 withstanding the sudden shocks and jars without injury.

What I claim is:—

1. A core cap comprising an inner sleeve, a spaced outer sleeve and an integral connecting web or rim, all formed of one piece of drawn metal, and a reinforcing member located in the annular space between the sleeves against which the unnotched end of the core may abut, said sleeves, web and reinforcing member being all notched or recessed to receive a driving key or member. 40

2. A core cap comprising an inner sleeve, a spaced outer sleeve and an integral connecting web or rim, all formed of one piece of drawn metal, and an annular reinforcing member located in the annular space between 50 the sleeves against which the end of the core may abut, said sleeves, web and reinforcing member being notched or recessed to receive a driving key or member, the wall of the notch being continuous at the sides and 55 bottom thereof.

3. A core cap comprising an inner sleeve, a spaced outer sleeve and an integral connecting web or rim, all formed in one piece of drawn metal, and an annular reinforcing 60 member located in the annular space between the sleeves, said sleeves, web and reinforcing member being notched or recessed to receive a driving key or member, and the said parts being interlocked at the walls of said notch 65 or recess.

In testimony whereof I have affixed my signature.

HOWARD PARKER.
